[57] CLAIM

The ornamental design for an articulated spotlight support arm, as shown and described.

DESCRIPTION

FIG. 1 is a perspective view of the articulated spotlight support arms in accordance with the present invention; FIG. 2 is a right side view of the articulated spotlight support arm shown in FIG. 1;

FIG. 3 is a left side view of the articulated spotlight support arm shown in FIG. 1;

FIG. 4 is a bottom plan view of the articulated spotlight support arm of FIG. 1 with the support arm in a vertical position;

FIG. 5 is a top plan view of the articulated spotlight support arm of FIG. 1 with the support arms in a vertical position;

FIG. 6 is a rear view of the articulated spotlight support arm shown in FIG. 1 with the support arms in a vertical position; and,

FIG. 7 is a rear view of the articulated spotlight support arm of FIG. 1 with the support arms in the position shown in FIG. 1.

The broken lines are shown for illustrative purposes only and form no part of the claimed design.
